WORLD CLOCK

Herman Schlacht, Woodhaven, N. Y.

Application February 20, 1935, Serial No. 7,340

6 Claims. (Cl. 58—43)

My invention relates particularly to clocks to be used in connection with all-wave radio sets. With the advent of these sets there has risen a demand for a timepiece which would enable one to determine quickly the time in the principal cities of the world. I am aware of the fact that numerous devices have been made for this purpose and those with which I am familiar are subject to the objection that they are complicated and too crowded in their information to be easily read.

My invention has for its object to provide a very simple device of this character and which will enable the user to obtain at a glance the required information.

My means of accomplishing the foregoing objects may be more readily understood by having reference to the accompanying drawings which are hereunto annexed and are a part of this specification, in which—

Fig. 1 is a front elevation of my improved clock;
 Fig. 2 is a side elevation of the same;
 Fig. 3 is a front elevation of one of the details;
 Fig. 4 is a rear view of the same together with
 25 the gear train connected therewith;
 Fig. 5 is a side view of the same;
 Fig. 6 is a vertical sectional view showing the
 interior construction;
 Fig. 7 is a side elevation of a modified form of
 30 my invention.

Similar reference numerals refer to similar parts throughout the entire description.

As shown in the drawings, I employ a standard clock movement 1. To this I fit my improvement. The movement 1 is mounted in a case 2, provided with the usual crystal 2'. In this case I cut a slot 3 which extends from one side of the base 4 around to the other side of the base. This slot 3 may be closed with any desired kind of
 40 transparent material 5. I have found celluloid serves the purpose very well. I provide a disc 6 having a circumferential flange 7 which fits inside of the case 2 and is provided with two sets of numerals 1 to 12 and 1 to 12 which may be printed upon a strip of paper which can be pasted or otherwise secured to the periphery of the flange 7. A stripe 8 is printed above one set of numerals and below the other to indicate a. m. and p. m. respectively. Upon the inside of the disc
 45 and adjacent a central opening provided for the hands of the clock I mount a gear 9 which meshes with the gears 10 which carry the hands 11 and 12, the ratio being such that the disc 6 will be rotated once in 24 hours. I provide an
 50 annulus 14 which has the numerals for the face

of the clock which is mounted intermediate the crystal 2' and the outer surface of the disc 6. I then scribe upon the exterior of the case 2 adjacent the slot 3 and on each side thereof a plurality of pairs of time zones arranged in a semi-circle, each pair bearing in opposition the names of various cities such as Kodiak, Moscow, Sitka, Baghdad, San Francisco, Nova Zembla, etc., their positions being determined by their longitude. Those above the stripe 8 are located in one hemisphere of the earth, while those below are in the opposite one. As a result when one wishes, for example, to determine the time at Singapore, when it is 9 o'clock in New York city, by glancing at the side of the clock for the city in question 15 and comparing it with the numerals on the disc he will be at once furnished with the time at that city. If the stripe 8 is above the numerals on the flange 7, it will be the hour indicated in a. m., on the other hand if the stripe 8 is below the numerals then it is the time indicated in p. m. It should be here noted that the places in the subdivisions immediately adjacent the stripe have the time indication according to whether the stripe is an a. m. or p. m. stripe while the places 20 located in the same subdivisions but on the opposite side of the time flange 7 and on the same side of the clock are the places which have time which is 12 hours distant from the places indicated on the first side, namely if it is 2 o'clock 25 p. m. in Tomsk, then it will be at the same instant 2 a. m. in Chicago. It will be obvious that by this arrangement I can have the various stations in print so large it can be read without any difficulty. If it is desired to have a greater number of stations, letters may be printed as shown in the divisions indicating the smaller cities and a book can be prepared giving the smaller stations for these subdivisions. In some cases it may be found desirable to have the case mounted, 30 as shown in Fig. 7 and when this is done the numerals may, if desired, be 1 to 24 or they can be as shown in the other figures. It will be apparent this may be done without departing from 35 the spirit of my invention. In this form the case 2' is laid on its side resting on a base 4'. A slot 3' is cut in the case. It may be covered with celluloid 5'. A disc similar to the disc 6 is provided having a circumferential flange 7' on 40 which may be printed the numerals. A stripe 8' divides the a. m. from the p. m. time.

For those locations which have daylight saving time I provide a third hand 13 which can be set for standard time; thus the clock will show the time 45

for the locality where the clock is used yet the hand 13 will give the standard time for locating the various foreign cities.

Having described my invention what I regard as new and desire to secure by Letters Patent is:

1. A world clock comprising a movement, a cylindrical casing having a circumferential slot cut therethrough, a disc having a circumferential flange thereon, two sets of numerals each from one to twelve arranged around said flange and visible through the slot, semi-circumferential lines on the flange to indicate one set of numerals as a. m. and the other p. m., means actuated by the clock movement to rotate said disc once in twenty-four hours and a plurality of subdivisions on the periphery of the case to indicate respective cities.

2. A world clock comprising a movement, a cylindrical casing having a circumferential slot cut therethrough, a transparent closure for said slot, a rotatable disc having a circumferential flange thereon, two sets of numerals each from one to twelve arranged around said flange and visible through said slot, semi-circumferential means to indicate one set of numerals as a. m. and the other p. m., means actuated by the clock movement to rotate said disc once in twenty-four hours and a plurality of parallel subdivisions on the periphery of the casing adjacent the slot to indicate respective cities.

3. A world clock comprising a movement, a cylindrical casing having a circumferential slot cut therethrough, a rotatable disc having a circumferential flange thereon visible through the slot, two sets of time numerals each from one to twelve arranged around said flange beneath the slot, means actuated by the clock movement to rotate said disc once in twenty-four hours, a plurality of parallel subdivisions on the periphery of the case to indicate respective cities, the said subdivisions arranged adjacent the slot and co-operating with the numerals for determining comparative times in different localities and offset

semi-circumferential lines on the flange to distinguish between a. m. and p. m.

4. A world clock comprising a movement, a cylindrical casing having a slot cut therethrough, a transparent closure for said slot, a rotatable disc having a circumferential flange thereon rotatable below the slot and visible therethrough, two sets of numerals each from one to twelve arranged around said flange and in line with the slot, offset parallel semi-circumferential lines on the flange adjacent the numerals to indicate one set as a. m. and the other p. m., means actuated by the clock movement to rotate said disc once in twenty-four hours, a plurality of parallel circumferentially arranged subdivisions on the periphery of the case and upon opposite sides of the slot to indicate respective localities and a plurality of characters in each subdivision.

5. A world clock including a movement, a cylindrical casing having a plurality of pairs of time zones determined by longitude and displayed in a semi-circle in opposed positions, each of said zones containing a geographical name of a city, two semi-circular stripes interposed between said zones and lying in different planes, the zones on one side of each stripe indicating a. m. and the other p. m., and means actuated by said clock movement to rotate said stripes.

6. A world clock including a movement, a cylindrical casing having a plurality of pairs of time zones determined by longitude and displayed in a semi-circle in opposed positions, each of said zones containing a geographical name of a city, two semi-circular stripes interposed between said zones and lying in different planes, the zones on one side of each stripe indicating a. m. and the other p. m., a set of numerals arranged adjacent each of said stripes and located adjacent each pair of zones, and means actuated by said clock movement to move said numerals and said stripes in units of time measurement.

HERMAN SCHLACHT.
